THE NORRIS PETERS CO., PHOTO-LITHO., WASHINGTON, D. C.

UNITED STATES PATENT OFFICE.

LANSING ONDERDONK, OF BOSTON, MASSACHUSETTS, ASSIGNOR TO THE UNION SPECIAL SEWING MACHINE COMPANY, OF CHICAGO, ILLINOIS, A CORPORATION OF ILLINOIS.

STITCH-FORMING MECHANISM FOR SEWING-MACHINES.

SPECIFICATION forming part of Letters Patent No. 703,813, dated July 1, 1902.

Application filed December 31, 1897. Serial No. 665,136. (No model.)

To all whom it may concern:

Be it known that I, LANSING ONDERDONK, a citizen of the United States, residing at Boston, in the county of Suffolk, State of Massachusetts, have invented certain new and useful Improvements in Stitch-Forming Mechanism for Sewing-Machines, of which the following is a description, reference being had to the accompanying drawings, and to the letters of reference marked thereon.

My invention relates to an improvement in sewing-machines, and particularly to sewing-machines of the chain-stitch type, in which an under-thread-carrying looper co-operates with the needle to form the stitch.

The object of the invention is to provide a spreading device for the under thread which seizes the latter or moves against it as the looper is beginning to recede from the needle-loop and as the needle is moving down and forces the thread to one side, so that the needle will pass between the looper and the looper-thread—that is, into the triangle, two sides of which are formed by the thread itself from the looper-eye to and around the end of the spreader to the point at which it is tied up with the needle-thread in the previous stitch, while the third side is formed by the looper itself, this arrangement reducing to a minimum the liability of skipping stitches.

The invention therefore consists in a so-called "spreading device" co-operating with the needle and looper and in proper relation to their respective movements to force the thread in such position that when the needle descends the thread will be in position to make the stitch and properly be surrounded by the looper-thread; and, further, the invention consists in certain combinations and arrangements of devices, as hereinafter referred to in the appended claims.

The invention is herein shown as applied to a sewing-machine for quilting purposes, in which a reciprocating and oscillating bar driven by suitable connections from the main shaft is provided with a large number of thread-carrying loopers arranged with their longitudinal axes at an angle to the longitudinal axis of their supporting-bar, this ar-

angement having been found of value and of practical necessity in adapting a well-known type of chain-stitch looper for use on a sewing-machine for quilting purposes.

The invention is illustrated in the accompanying drawings, in which—

Figure 1 is a top plan view of so much of a sewing-machine for quilting purposes as is necessary to an understanding of my invention. Figs. 2 to 6, inclusive, represent plan views showing the looper and spreader in different relative positions; and Fig. 7 is an end view of Fig. 1, partially in section.

In the drawings, E represents a driving-shaft, which may or may not be the main shaft of the quilting-machine, and from this, by suitable connections to the looper rocker-shaft H, power is applied for reciprocating and oscillating the looper-supporting bar h', which is attached to the looper rocker-shaft H.

J represents the loopers, and Figs. 1, 2, 3, 4, and 5 represent the different positions of the loopers and loop-spreaders in forming the stitches.

K represents an upright shaft supported on the bracket A, while B is an operating-lever to which the loop-spreading bar F, carrying the loop-spreaders G, is secured.

D and d are quarter bevel-gears, which operate the revolving upright shaft K. The loop-spreader bar F, in which the loop-spreaders are secured by set-screws, is secured to the levers B in a manner that admits of accommodating itself to the movements of said levers B at the point of connection b². The revolving shaft E operates the upright shafts K, and consequently the head C, secured thereon, and to this head C are freely secured by studs c' the levers B, and these levers B rock and slide on the fulcrumed stud a³, which is secured in an arm of the bracket a' at a³, and thus by a complete revolution of the shaft E an elliptic movement is given to the bar F and the loop-spreaders G.

Fig. 2 shows the position of the parts as the looper begins its backward movement. Fig. 3 shows the loop-spreader in a different position and released from the looper-thread looper. Fig. 4 shows the parts having moved farther

back. Fig. 5 shows the position as the looper is moving forward, just entering the needle-loop, and Fig. 6 represents the loop-spreader moving forward preparatory to engaging with the looper-thread, the looper just beginning to move backward, this being the position of the parts shown in Fig. 1.

While I have shown this invention as applied to a sewing-machine for quilting purposes, it will be understood that the same arrangement may be applied in connection with the driving-shaft of an ordinary sewing-machine using a small number of loopers and loop-spreaders.

Having thus described my invention, what I claim as new, and desire to secure by Letters Patent, is—

1. In a sewing-machine, a looper, a support therefor upon which the looper is arranged, with its longitudinal axis diagonal to the direction of length of the support with means for oscillating said support, a loop-spreader sup-

port, and a spreader arranged thereon with its longitudinal axis at an angle to the longitudinal axis of the looper and means for reciprocating said latter support both in the direction of the length of the spreader, and transversely thereto; substantially as described. 25

2. In a sewing-machine, a driving-shaft, a bar or frame, having a pivotal sliding connection with a fixed part of the machine-frame, a crank for sliding and oscillating said bar or frame on its pivot, and a spreader-support pivoted to said bar or frame; a spreader thereon, and a looper and support therefor, with means for operating it substantially as described. 30

In testimony whereof I affix my signature in presence of two witnesses.

LANSING ONDERDONK.
